UNITED STATES PATENT OFFICE.

WENDELL P. THORÉ, OF BOSTON, MASSACHUSETTS, ASSIGNOR TO GENERAL ELECTRIC COMPANY, A CORPORATION OF NEW YORK.

DESIGN FOR A LIGHT-FIXTURE.

42,528.

Specification for Design.

Patented May 14, 1912.

Application filed March 28, 1911. Serial No. 617,536. Term of patent 14 years.

To all whom it may concern:

Be it known that I, WENDELL P. THORÉ, a citizen of the United States, residing at Boston, in the county of Suffolk and State of Massachusetts, have invented a new, original, and ornamental Design for Light-Fixtures, of which the following is a specification.

The accompanying drawing is a view illustrating my novel design.

What I claim, is,—

The ornamental design for a light fixture as shown.

In witness whereof, I have hereunto set my hand this twenty-fifth day of March, 1911.

WENDELL P. THORÉ.

Witnesses:

JOHN A. McMANUS, Jr.,

GUY N. CHAMBERLIN.
